UNITED STATES PATENT OFFICE.

WILLY H. LAU, OF CHICAGO, ILLINOIS.

DESIGN FOR A SHELL FOR LIGHTING-FIXTURES.

49,063.

Specification for Design.

Patented May 16, 1916.

Application filed May 9, 1914. Serial No. 837,607. Term of patent 3½ years.

To all whom it may concern:

Be it known that I, WILLY H. LAU, a citizen of the United States, residing at Chicago, in the county of Cook and State of Illinois, have invented a new, original, and ornamental Design for a Shell for Lighting-Fixtures, of which the following is a specification, reference being had to the drawing accompanying and forming a part hereof.

The figure is a perspective, looking up,

of a shell for lighting fixtures, showing my new design.

I claim:—

The ornamental design for shell for lighting fixtures as shown.

WILLY H. LAU.
